LENS EDGER

Ezra H. Neval, 2392 W. 7th St., Los Angeles, Calif.
Filed May 27, 1959, Ser. No. 816,328
14 Claims. (Cl. 51—101)

This invention has to do with apparatus for grinding and finishing the edges of lenses, such as spectacle lenses, and has as an object the provision of a machine which has novel and efficient mechanical actuating means for controlling the driving mechanism to carry out an edge grinding and finishing operation.

An additional object is to provide a machine of this character which is capable of completing a grinding operation during a single revolution of the lens.

Another object is to provide a machine of this character which incorporates novel and efficient chuck means for holding the lens during the grinding operation.

Another object is the provision of a lens edging machine which includes novel means for centering and aligning the lens between opposed chucks.

A further object is to provide a construction of this character which has novel features of adjustability.

Another object is to provide a lens edger having adjustable means for varying the pressure of a lens edge against the grinder wheel.

A still further object is to provide novel means for insuring the proper centering of a lens between the lens holding chucks.

Other objects and corresponding advantages will appear hereinafter.

While I shall point out in the appended claims the features which I believe to be new, I shall now, for the purpose of making clear to those skilled in the art how to carry my invention into practice, describe a presently preferred embodiment thereof, for which purpose I shall refer to the accompanying drawings, wherein:

FIG. 1 is a side elevational view;

FIG. 2 is a front elevational view;

FIG. 3 is a reduced view taken on line 3—3 of FIG. 2;

FIG. 4 is an enlarged view taken on line 4—4 of FIG. 2;

FIG. 5 is a reduced view taken on line 5—5 of FIG. 6;

FIG. 6 is an enlarged view taken on line 6—6 of FIG. 5;

FIG. 7 is a fragmentary view, partly in section and partly in front elevation, showing the head mounting;

FIG. 8 is a view taken on line 8—8 of FIG. 7;

FIG. 9 is a fragmentary section taken on line 9—9 of FIG. 7;

FIG. 10 is a view taken on line 10—10 of FIG. 4;

FIG. 11 is a view taken on line 11—11 of FIG. 10;

FIG. 12 is a perspective view of a device for centering the lens when it is being mounted between the chucks; and

FIG. 13 is a perspective view showing a lens marking element.

Referring now to the drawings, the numeral 5 denotes a base, from the rear end of which an upright portion 6 extends. The upright 6 has a back wall 6a, side walls 6b and a top wall 6c. A conventional electric motor M is mounted on the rear end of the base.

A grinder wheel 15 is secured on a shaft 17 journaled in bearings 18 carried by the base. The hub portion 19 of the wheel engages the contiguous ends of the bearings 18. An oil cup 20 is provided for each bearing, and each bearing is secured on the base by bolts and nuts 21.

A pair of pulleys 25 of relatively different diameters are secured on the left end of shaft 17 to selectively receive a continuous belt 26 which also extends about a selected one of a pair of pulleys 27 of relatively different diameters mounted on the motor shaft 28.

As best shown in FIGS. 2 and 3, the grinder wheel has

2

a relatively wide peripheral surface portion 15a and a V-grooved portion 15b.

On the right-hand end of the shaft 17, I secure a pair of pulleys 30, of relatively different diameters, from any selected one of which pulleys a continuous belt 32 extends about any selected one of a pair of pulleys 35 (FIG. 6) mounted on a shaft 37 journaled in a bearing 38 carried by a side wall 6b of the upright 6. The pulleys 35, while secured together, are both mounted for free rotation on and relative to the shaft 37. A flexible, driven shaft 40 is secured on the left-hand end of the shaft 37 by a suitable connector 42.

A gear 45, disposed in a housing 47, is secured on shaft 37 for cooperation with a clutch mechanism, generally denoted 50, to be hereinafter described. The inner pulley 35a is resiliently frictionally connected to the gear 45 only by an arched leaf spring 52, so as to permit slippage as between pulley 35a and gear 45 when the gear 45 is subjected to the braking action of the clutch 50.

The clutch 50 (FIGS. 5 and 6) includes a pinion 55 rotatably carried on a spindle 57. A clutch disc 58 is secured on the inner end of the pinion 55, the disk rotating between a resilient pad 60, carried on the inner end of an adjustment screw 62, and a resilient pad 64 secured on the free end of a leaf spring 65 which latter is secured at its inner end to the wall 6b as by a rivet 66. The spring 65 normally urges the pad 64 to the left, or out of braking engagement with the disk 58. The spindle 57, on which pinion 55 is mounted, is, as shown in FIG. 5, carried by an arm 67 of a bell crank 61 pivoted to side wall 6b of the upright 6 by pivot pin 62. The other arm 67a of the bell crank may be used for swinging the crank about the pivot 62 to disengage the pinion 55 from gear 45 when desired.

The pad 64 is, as shown in FIG. 6, normally in yieldable engagement with the disk 58 by pressure exerted by wire 63, so that the disk and the pinion are normally braked to prevent rotation of the gear 45. However, when pressure exerted by wire 63 is relieved the pad 64 is moved, by the spring 65 out of braking engagement with the disk so that the gear 45 is free to rotate, causing the shaft 37 to rotate. This brake releasing movement of the pad 64 is effected by axial movement of a wire 63 axially mounted in a flexible tube 68. The mechanism for so moving the wire 63 will be hereinafter described.

Means for chucking and rotating the lens blank relative to the grinder wheel will now be described.

I provide a head member 70 which is mounted for both vertical and lateral adjustment relative to the grinder wheel in the following manner (FIGS. 7—9):

As best shown in FIGS. 7—9, a screw 67 is mounted uprightly within the portion 6 of the base and has a pointed bottom end which engages a threadedly adjustable support 67a carried by the base. The top end of this screw is axially socketed to receive the squared bottom end (not shown) of an actuating pin 69 journaled in the top wall 6c of the upright portion of the base; the pin carrying handle 69a to facilitate manually rotating it. An internally threaded sleeve 71 threadedly engages screw 67 and is restrained from rotating with the screw by means of an arm 76 whose inner end is fixed to the sleeve in embracing relationship thereto. The sleeve 71 has, at its top end, a relatively large exterior portion 71a which has an integral crossarm portion 71b presenting a diagonal left end portion 71c (FIG. 9), and has bracket portions 71d, one on each side of the portion 71a. Link member 77 is pivotally connected to a bracket portion 71d by pivot member 71e; and the head 70 is rigidly secured to the outer end of the link 77, as by bolt 77a.

It will be observed that the pivotal connection of the link 77 to the bracket portion 71d is such as to permit swinging of the link 77 as well as the head in a vertical

spring (not shown) is mounted in the post 164 below the bottom end of the pin 166 so that the pin is normally urged outwardly of the post. A cup 177 is carried by another portion of the top surface of the base and within the cup there is an inked pad 178.

In using the lens marking element, the user first rotates the knurled knob portion 179 of the pin to swing the disk 172 into position above and in register with the cup 177. The user then depresses the pin 166 to cause the fingers 174 to engage the inked pad 178 to receive a coating of ink. The user then returns the disk into position above and in register with the lens blank L on the pad 175 and depresses the pin 166 to cause the fingers to resiliently engage and apply markings 180 to the lens at points spaced apart 90° adjacent the periphery of the lens blank.

The lens applying and retaining device 161 (FIG. 12) includes a clamp having two relatively swingable spring-loaded jaws 185, 186 pivotally secured together between their ends at 187.

The jaw 186 has a bifurcated outer end portion 189. The bifurcations are parallel at their outer end portions 189a and curved at and adjacent their intersecting portions 189b. The top surface of the bifurcations is cut away to provide a recess 190 to conform to the peripheral portion of either of the chucks, and carries a plurality of soft pads 191 as well as 90° spaced marking indicia 192. The bifurcated top jaw 185 clamps the marked lens blank L, shown in FIG. 13, against the pads and with the indicia markings 180 on the lens in register with the indicia markings 192 on the jaw 186. The bottom jaw 186 also carries, at the intersection of the bifurcations, an outwardly projecting finger 193 for engagement in a peripheral slot 105 in a selected one of the chucks.

Thus, after the lens blank is marked in the marker shown in FIG. 13 and mounted between the jaws of the holder 161, the chucks are separated and the holder 161, with its carried lens blank, is inserted between the chucks with the cut-away portion 190 of the jaw 186 engaging over substantially 180° of the peripheral surface of the chuck at the outer edge of the latter, and with the finger 193 engaging in the slot 105. This insures that the lens blank is properly centered between the chucks.

For maintaining the periphery of the grinder wheel wetted during grinding, I provide a water container 200, supported on top wall 6c. A manually controllable outlet valve 202 is provided for the container outlet to deposit water from the container into the funnel-like inlet end 203 of a conduit 205 whose discharge end is positioned to deposit the water on the periphery of the grinder wheel.

Operation

The user installs a template 83 on the chuck shaft 85, the periphery of the template defining the desired peripheral shape to which the lens blank is to be ground. The knob 102 is then unscrewed to allow the spring 90 to move the chuck shaft 73 axially to the right in FIG. 3 to separate the chucks. After having marked the lens and mounted it in the clamp device 161, the user positions the lens in centered position between and relative to the chucks, after which the knob 102 is rotated to cause the spring 90 to move the chuck shaft 73 axially to the left to clamp the lens blank between the chucks.

In edging some lenses, it is desirable first to grind the periphery of the lens blank generally to the shape desired by engaging the periphery of the lens blank with the flat surface portion 15a of the grinder wheel. Then, after this first grinding operation, the head 70 may be swung to the right and lowered into the position of FIG. 2 to bring the lens blank into register with the grooved portion 15b of the grinder wheel.

To lower bracket 138 and its carried clutch-actuating elements into position to cause the lens blank to engage

in groove 15b, the user swings the lever 152 to operate the cam 154.

The nut 148 is rotated manually to bring the shoe 142 into the desired position in relation to the template to cause the lens to be ground to the desired diametric dimensions. The head is then swung laterally to a position to cause the periphery of the lens to be registerable with either the flat portion 15a or the grooved portion 15b of the grinder wheel and is then lowered until the lens 10 engages the grinder wheel.

Then the motor control switch 172 is closed to start the motor M.

Inasmuch as the clutch normally prevents rotation of drive shaft 40, thus normally preventing rotation of the 15 chucks, the edge of the lens will continue to be ground off by the grinder wheel until sufficient is ground off to cause the template to depress the shoe 142. When this occurs, the bell crank 135 will function to disengage the pad 64 from the clutch disk, permitting shaft 40 to be rotated by pulley 35. Thus the chucks will be rotated until a next adjacent high point of the lens edge is reached, which causes the template to again depressingly engage the shoe 142, which will again cause the clutch to arrest rotation of gear 45 and thereby stop rotation of the 25 chucks until the high point of the lens edge is ground off. The foregoing-described sequences of operation continue until the lens has been rotated through a complete revolution.

If it should be desired temporarily to eliminate the 30 control of the rotation of the chucks effected by engagement of the template with the shoe 142, so that the chucks might be rotated continuously rather than intermittently, this can be accomplished by the user swinging lever 67a to the left, in FIG. 5, to free the clutch pinion 35 55 from engagement with gear 45. Normally the clutch pinion is resiliently held in engagement with said gear by a spring 210.

I claim:

1. In a lens grinding machine, a driven grinder wheel, 40 lens-carrying chucks rotatably supported for adjustment relative to said grinder wheel, a drive shaft operatively connected to said chucks, a template supported for rotative movement with such chucks, a power-driven pulley mounted on said drive shaft for rotation relative thereto, a gear secured on said drive shaft, a slip connection between said gear and said pulley, a bell crank supported in position for engagement by said template and a brake operably associated with said bell crank for arresting rotation of said gear whereby to cause said pulley to rotate relative to said drive shaft.

2. In a lens grinding machine, a driven grinder wheel, lens-carrying chucks rotatably supported for adjustment relative to said grinder wheel, a drive shaft operatively connected to said chucks, a template supported for rotative movements with such chucks, a power-driven pulley mounted on said shaft for rotation relative thereto, a gear secured on said shaft, a slip connection between said gear and said pulley, a bell crank supported in position for engagement with said template, a clutch including a pinion rotatably supported in meshing engagement with said gear, a disk carried by said pinion for rotation therewith, a disk-engaging brake, a spring supporting said brake, said spring normally urging said brake out of engagement with said disk, and mechanical means connecting said bell crank to said spring whereby normally to cause said spring to hold said brake in engagement with said disk; said mechanical means being operable in response to movement of said bell crank in one direction to cause said spring to move said brake out of engagement with said disk.

3. The machine of claim 2 wherein said bell crank is supported for adjustment relative to said template.

4. The machine of claim 2 wherein said means connecting said bell crank to said spring comprises a flexible 75 wire axially slideably mounted in a flexible tube and

wherein said wire and tube are movable into bowed position in response to movement of said bell crank.

5. In apparatus for grinding the edge of a lens, a body, a power-driven grinder wheel rotatably carried by said body, a head member supported by said body for movement towards and away from the grinding surface of said grinder wheel, chuck shafts rotatably carried by said head member in coaxial alignment, one of said chuck shafts being axially adjustably movable towards and away from the other, a pair of chucks carried by said respective shafts, said chucks being disposed to clampingly engage therebetween a lens to be ground with its edge in engagement with said grinding surface, a template carried by one of said chuck shafts coaxial with the said chucks, means for controllably rotating said chuck shafts, including a drive shaft operatively connected to said chuck shafts, a driven pulley mounted on said drive shaft for rotation relative thereto, a gear secured on said drive shaft, spring means interposed between and resiliently engaging said pulley and gear and constituting the sole driving connection between said pulley and said gear, brake means operatively associated with said gear to arrest rotation thereof whereby to arrest rotation of said drive shaft, and mechanical brake-actuating means carried by said body in position to be operatively engaged by said template.

6. The apparatus of claim 5 wherein said brake means includes a pinion meshing with said gear, a disk coaxial with and secured to said pinion, and braking means carried by said body for movement into and out of braking engagement with said disk.

7. The apparatus of claim 6 which additionally includes means for moving said pinion out of meshing engagement with said gear whereby to render said brake means inoperative.

8. In apparatus for grinding the edge of a lens, a body, a power-driven grinder wheel rotatably carried by said body, a head member supported by said body for movement towards and away from the grinding surface of said grinder wheel, chuck shafts rotatably carried by said head member in coaxial alignment, one of said chuck shafts being axially adjustably movable towards and away from the other, a pair of chucks carried by said respective shafts, said chucks being disposed to clampingly engage therebetween a lens blank to be ground with its edge in engagement with said grinding surface, a template secured on one of said chuck shafts coaxial with the said chucks, means for controllably rotating said chuck shafts; said last-named means including a spring-loaded bell crank pivotally carried by said body in position to have one of its arms engaged by said template, a drive shaft rotatably carried by said body and operatively connected to said chuck shafts, a driven pulley mounted on said drive shaft for rotation relative thereto, a gear secured on said drive shaft adjacent said pulley, spring means interposed between and resiliently engaging said pulley and said gear and constituting a slippable friction driving connection between said pulley and said gear, brake means operatively associated with said gear to arrest rotation thereof and including a pinion rotatively supported for meshing engagement with said gear, a disk secured to said pinion coaxially therewith, a resilient pad, a leaf spring secured at one end to said body and supporting said pad at its other end in position to engage and disengaged from said disk, and said spring normally

urging said pad out of engagement with said disk, and actuating means connecting the other arm of said bell crank to said leaf spring and being operative in response to pressure engagement of said template with said first-mentioned arm of said bell crank to permit said leaf spring to move said pad out of braking engagement with said disk.

9. The apparatus of claim 8 wherein said actuating means comprises a flexible wire and a flexible tubular housing for said wire, said wire being axially movable with relation to said housing.

10. The apparatus of claim 8 which additionally includes a crank member supporting said pinion for movement into and out of meshing engagement with said gear.

11. The apparatus of claim 8 which additionally includes a second resilient pad disposed in opposed relationship to said first-mentioned pad at the opposite side of said disk, and adjustable screw means supporting said second resilient pad in position to engage said disk in opposition to said first-mentioned resilient pad.

12. The apparatus of claim 8 wherein said bell crank is adjustable toward and away from said template.

13. In apparatus for grinding the edge of a lens, a body, a lens grinding wheel drivingly carried by said body, a head member adjustably carried by said body, lens carrying chuck means rotatably carried by said head member, means for rotating said chuck means, a template operatively associated with said chuck means for controlling the peripheral shape of said lens, a mechanical clutch operative in response to grinding of said lens by said grinding wheel to intermittently cause rotation of said chuck means, mechanical clutch actuating means operatively associated with said template, and mechanical means for rendering said clutch means inoperative and to cause continuous rotation of said chuck means.

14. The apparatus of claim 13 in which said clutch means includes a spring loaded control element and wherein said clutch actuating means includes a bell crank operatively associated with said template, a flexible tube, and a flexible wire axially slidably mounted in said tube, said wire being operably connected at one end to said bell crank and operably connected at its other end to said spring loaded clutch control element and being operative to move said last named element in one direction by bowing laterally in response to movement of said bell crank.
